UNITED STATES PATENT OFFICE.

PHILIPP SEILER, OF CHICAGO, ILLINOIS, ASSIGNOR TO MONROE KOHN,
OF CHICAGO, ILLINOIS.

COMBINED CIGAR-CUTTER AND MATCH-SAFE.

SPECIFICATION forming part of Letters Patent No. 761,547, dated May 31, 1904.

Application filed January 19, 1903. Serial No. 139,633. (No model.)

To all whom it may concern:

Be it known that I, PHILIPP SEILER, a citizen of the United States, residing at Chicago, county of Cook, State of Illinois, have invented 5 a certain new and useful Improvement in a Combined Cigar-Cutter and Match-Safe; and I declare the following to be a full, clear, and exact description of the invention, such as will enable others skilled in the art to which 10 it pertains to make and use the same, reference being had to the accompanying drawings, which form a part of this specification.

My invention relates in general to cigar-cutters, and more particularly to a combined 15 cigar-cutter and match-safe.

In order to cut off the tip of a cigar and then ignite the same with a match, the smoker must have a cigar-cutter and a match-safe, which are ordinarily two separate devices, 20 each of which is used separately.

The object of my invention is to provide a combined cigar-cutter and match-safe, thereby rendering it only necessary for the smoker to carry with him and to handle a single device in order to perform the operation of cutting off the tip of a cigar as well as lighting the same.

A further object of my invention is to provide a combined cigar-cutter and match-safe 30 which will be simple in construction, inexpensive in manufacture, and convenient in use.

My invention, generally described, consists in a casing provided with a hole through which the tip of the cigar is inserted, a plate 35 located within the casing and movable relatively thereto and having a cutting edge adapted to be moved across the hole in the casing when the plate is reciprocated, a box guided in the casing and movable relatively 40 thereto, said plate being engaged by said box to force the cutting edge across the hole in the casing, and a lug on said plate projecting into the box to limit the outward movement thereof.

45 My invention will be more fully described hereinafter with reference to the accompanying drawings, in which the same is illustrated

as embodied in a convenient and practical form, and in which—

Figure 1 is a perspective view showing the 50 match-box partially withdrawn from the casing; Fig. 2, a plan view of the bottom of the device; Fig. 3, a longitudinal section, on an enlarged scale, taken on line 3 3, Fig. 2; Fig. 4, a cross-sectional view on line 4 4, Fig. 3; 55 and Fig. 5, a fragmentary detail view taken on line 5 5, Fig. 4.

Similar reference characters are used to designate similar parts in the several figures 60 of the drawings.

Reference character A indicates a casing comprising a flat top with downwardly-extending sides A² and an end A'. The end of the casing opposite to the end A' is open. The lower edges of the sides A² are provided 65 with inturned flanges a², while the end A' is provided with an inturned flange a'. The top of the casing is provided with a hole a, preferably located near the end A' thereof. The end of the top of the casing A, opposite 70 to the end A' is cut away, as shown at a⁴, a distance corresponding to the diameter of the hole a.

B indicates a plate which is guided within the casing A. The plate B consists in side 75 portions B², each of which is bent inwardly to form flanges b². The depth of the sides B² is such as to fit within the casing A', between the top thereof and the inturned flanges a². The flanges b² slide upon the flanges a² when 80 the plate and box are relatively moved and retain the top of the plate B in close contact with the under surface of the top of the casing. A blade or cutting edge b is provided upon the plate B and normally occupies a position adjacent to the edge of the hole a in the casing. The portions of the plate B at either side of the blade b are turned downwardly to form lugs b'.

A spring C is interposed between the inner 90 surface of the end A' of the casing and the lugs b' on the plate B. This spring is shown as comprising a straight intermediate portion c, which engages the interior of the end A' of

the casing, and end portions c' , each of which extends across the space between the opposing ends of the casing and plate, as clearly shown in Figs. 2 and 3. The ends of the crossed portions c' of the spring bear against the lugs b' on the plate. In order to prevent the spring C from forcing the plate out of the casing, the side walls of the latter are provided with in-turned flanges a^3 , which extend around the ends of the sides B^2 of the plate B.

A box D fits within the plate B, so as to be guided thereby. The inner end of the box engages the lugs b' , while the outer end of the box is preferably flush with the ends of the side walls of the casing and plate. In order to prevent the box from being entirely withdrawn from the plate, a lug b^3 is preferably bent downwardly from the top of the plate, so as to project into the path of movement of the rear wall of the box. The under side of the box is preferably provided with a hole d' , through which the finger of the user may be slightly inserted to elevate the matches above the box, so that they may be readily removed.

If desired, a loose plate or card D' may be placed upon the bottom of the box, thereby insuring the elevation of all of the matches in the box upon the finger of the user being inserted in the hole d' .

The operation and manner of using my invention are as follows: When it is desired to use the device as a cigar-cutter, the tip of the cigar is inserted through the hole a and pressure is applied to the outer end of the box D. The pressure applied to the box is communicated to the plate B through the engagement of the lugs b' thereon with the rear wall d of the box. The cut-away portion a^4 in the top of the casing permits the box, and with it the plate, to move inwardly, thereby placing the spring C under tension and moving the blade b across the opening a , whereby the tip is cut off of the cigar. Upon the pressure on the end of the box being discontinued the spring returns the plate and with it the box to their normal positions, the flanges a^3 on the side walls of the casing serving as stops to limit the movement of the plate. When it is desired to remove a match from the box, the latter is slid forward with respect to the plate and casing a distance sufficient to enable a match to be removed. The lug b^3 on the plate serves as a stop to prevent the entire removal of the box.

From the foregoing description it will be observed that I have invented a combined cigar-cutter and match-safe the parts of which are so arranged as to render the device small and compact, so as to be readily carried by the smoker. It will be further observed that the box which holds the matches receives the pressure for actuating the cigar-cutter, while it in turn is guided within the plate upon which the cutter is formed and is prevented

from removal by a lug on the plate. The casing, it will be noticed, serves as a guide for and surrounds the plate which supports the cutter and retains the cigar in position to have the tip thereof removed by the blade. In other words, the entire device consists in but three parts, each one of which co-operates in forming both the cutter and the match-safe.

While I have described more or less precisely the details of construction, I do not wish to be understood as limiting myself thereto, as I contemplate changes in form, the proportion of parts, and the substitution of equivalents as circumstances may suggest or render expedient without departing from the spirit of my invention.

I claim—

1. In a combined cigar-cutter and match-box, the combination with a casing having a hole therein, of a reciprocating plate guided in said casing, a blade carried by said plate, a spring interposed between the adjacent ends of the casing and plate and normally retaining the blade at one side of the hole in the casing, stops on the casing engaged by the plate to limit the movement thereof by the spring, and a box in sliding engagement with said plate and adapted to move said plate against the tension of said spring to thereby reciprocate said blade.

2. In a combined cigar-cutter and match-box, the combination with a casing having a hole therein, a reciprocating plate guided in said casing, a blade formed integrally with said plate, lugs formed on said plate by bending the portions on either side of said blade, a spring interposed between the end of the casing and lugs, and normally retaining the blade at one side of the hole in the casing, and stops on the casing engaged by said plate to limit the movement thereof by the spring.

3. In a combined cigar-cutter and match-box, the combination with a casing having a closed end and having a hole through the top thereof adjacent to the closed end, a reciprocating plate guided in said casing, a blade carried by said plate, a spring interposed between the closed end of the casing and the plate, stops on the casing to limit the movement of the plate under the spring tension, a box guided within said plate and adapted to move said plate toward the closed end of the casing and thereby compress the spring and force the blade across the hole in the casing, said box being uncovered by a movement in the opposite direction.

4. In a combined cigar-cutter and match-box, the combination with a casing having a hole through which the tip of the cigar is inserted, a reciprocating plate guided in said casing, a blade carried by the plate, lugs formed on said plate by bending the portions thereof at either side of the blade, a spring interposed between said casing and said lugs, a box guided

within said plate and adapted to engage said lugs to move the blade across the hole in the casing.

5. In a combined cigar-cutter and match-safe, the combination with a casing having a hole through the top thereof near one end and having its top cut away at its other end, a reciprocating plate guided in said casing and extending beneath said cut-away portion of the top thereof, a blade carried by said plate, lugs formed on said plate by bending the portions thereof at either side of the blade, a spring interposed between the casing and said lugs and normally retaining the blade at one side 35 of the hole, a box guided within said plate and adapted to engage said lugs and thereby move said blade across said hole a distance corresponding to the cut-away portion in the top of the casing.
20. 6. In a combined cigar-cutter and match-box, the combination with a casing having a hole through which the tip of a cigar may be inserted, of a sliding plate within said casing, a blade carried by said plate, a box sliding within said plate and adapted to move the same 45 within said casing, and a lug extending from said plate into the path of movement of the box to limit the outward movement thereof.
25. 7. In a combined cigar-cutter and box, the combination with an open-top box, of a coöperating part extending over the top of the box 50

and having a hole therethrough, said box being movable in opposite directions relatively to said part, a blade movable with respect to said hole, a spring the tension of which normally retains said blade at one side of said hole, said blade adapted to be moved across the hole by a movement of said box in a direction to place said spring under tension, said box being uncovered to permit access thereto 40 by a movement in an opposite direction.

8. In a combined cigar-cutter and box, the combination with a casing having a hole therethrough, of an open-top box guided within said casing and adapted to move relatively thereto 45 in opposite directions, a blade adapted to reciprocate across said hole, a spring the tension of which normally retains said blade in a position to uncover said hole, said blade adapted to be reciprocated across said hole by a movement of the box in a direction to place the spring under tension, said box being uncovered to permit access thereto by a movement relatively to the casing in an opposite direction.

55 In testimony whereof I sign this specification in the presence of two witnesses.

PHILIPP SEILER.
